GAME POINTER AND SCORER

Edward W. Piper, Woodbrook, Md.

Application April 10, 1947, Serial No. 740,594

7 Claims. (Cl. 235—88)

1

The present invention relates to a game pointer and scorer to be used in playing contract or auction bridge, hearts, five-hundred and other similar games in which cards are used.

One of the objects of the present invention is to provide a device that will enable each player or score keeper to keep track of such features of a game as the bid, the dealer and to compute the score of a hand played.

Another object of the present invention is the provision of a device that will eliminate arguments that may arise as to the bids of the respective players.

A still further object of the present invention is the provision of a device that is small and compact, one that may easily be carried in a pocket or pocket-book, or held in the palm of a hand.

A still further object of the present invention is the provision of a device in which a player may determine at a glance, what the bid was; whether vulnerable or not vulnerable; who the dealer is and/or was; and the points the winner of a hand is entitled to.

A still further object of the present invention is the provision of a plurality of graduated discs superposed one upon the other, and secured together for rotatable movement.

The invention herein described and illustrated is directed to a game of bridge, but I wish to have it distinctly understood that it may be adapted for other games.

Other objects of the present invention will be more readily understood from the following description of the preferred form when taken in conjunction with the accompanying drawing, in which:

Figure 1 is a top plan view of a base disc.

Figure 2 is a plan view of a smaller disc that is superposed upon the base disc.

Figure 3 is a plan view of a still smaller disc that is superposed upon the disc shown in Figure 2.

Figure 4 is an assembled plan view of the discs.

Figure 5 is a plan view of the reverse face of the base disc.

Referring to the drawings the numeral 10 represents my game indicator and scorer that may be made of any suitable material, and it comprises three discs, disc 11 with a central aperture 12, disc 13 with a central aperture 14 and disc 15 with a central aperture 16, the discs being loosely secured together by an eye-rivet 17, the discs being adapted for rotatable movement.

Upon the face 18 of the disc 11 there is stamped or otherwise imprinted semi-concentric circles 19, 20, and 21, and segmental division lines 22 that separate certain indicia from other indicia to be referred to later. The semi-concentric circle areas 23 are of a length of approximately 72°.

2

and in this area there is indicia 24 labeled "Vulnerable." The area 25 which is approximately 72° is divided into segmental spaces 26 by the segmental division lines 22 and into the spaces 26 there is provided numerals from 1 to 5 inclusive, and letters L. S. and G. S., L. S. being the abbreviation for Little Slam and G. S. for Grand Slam, the numerals and abbreviations being as stated in the segmental spaces 26.

10 The semi-concentric circle areas 27 contain indicia 23 labeled "Not vulnerable" and the semi-concentric area 29 contains numerals from 1 to 5 and abbreviations L. S. and G. S. representing Little Slam and Grand Slam respectively, and it
15 is to be noted that the numerals and abbreviations are in line with the segmental division lines 22. It is also to be noted that the segmental divisional lines extend below the semi-concentric circle 19 and above the middle semi-concentric circle 20. Arrows 30 in the areas 23 point to the numerals and abbreviations in the segmental divisions, and arrows 31 point to the numerals

and abbreviations in the area 29. Superposed upon the disc 14 is disc 13, the central opening 14 adapted for alignment with the opening 12 in disc 14. The disc 13 is provided with five pyramidal pointers 32 that extend out from the peripheral edge of the disc and as shown in Figure 4, the apices 33 of the pointers 32 are in approximate alignment with the semi-concentric circle 19. In one of the pointers there are provided the letters N over T, the letters being the abbreviation for the words No Trump, and following around in a clockwise direction is the representation of a Spade, Heart, Diamond and Club, representing the suits in a deck of cards. In the actual device the Spade and Club would be shown in black, the Heart and Diamonds in red. The disc 13 is provided with concentric

40 circles 34 and 35 and with divisional lines 36. The apices 33 of the pointers 32 are in spaced relation of 72° . The divisional lines 36 are in spaced relation to each other of 72° , and it is to be noted that the divisional lines are in spaced 45 relation mid-way the pyramidal pointers of 36° on each side of the divisional lines. Within the concentric area 37 and on the left of each of the divisional lines 36 are the letters R. D. B. L. being the abbreviation for "redouble," and to the right 50 of the divisional lines 36 is the letters D. B. L. being the abbreviation for "double."

The disc 15 illustrated in Figure 3, known as the dealer pointer and having a central opening 16 that is adapted for alignment with the openings 14 and 12. Extending out from the peripheral edge of the disc 15 are pyramidal pointers 38 the apices 39 of the pointers being in spaced relation of 90°. Within the pyramidal pointers, starting at the top and following around the disc 60 in a clockwise direction are the letters N repre-

senting North, E representing East; S representing South and W representing West. Disc 15 is provided with concentric circles 40 and 41 and within the concentric area 42 is the word "dealer" under each of the four pyramidal pointers 38.

The reverse face of Figure 1 is illustrated in Figure 5, and it has imprinted thereon the scoring rules. The face 43 is divided into five segments of 50° each, and five segments of 22° each. The face is provided with a plurality of concentric circles, the circle 44 being spaced from the peripheral edge of the disc. In the concentric area 45 is the word Penalties, and following around in a clockwise direction is area 46 titled Over-tricks, area 47 titled Slams, area 48 titled Honors, area 49 titled Rubbers, and area 50 titled Trick-scores. Under each one of the titled areas is an orderly arrangement of sub-titles and numerals so that players may determine their scores.

In the operation of the indicator and scorer and by way of example:

North deals, a bid of 4 No-Trump is made, Not Vulnerable and Not Doubled or Redoubled. The pointer NT on the disc 13 is turned to the numeral 4 on the scoring range 29 Not Vulnerable. The N on the small disc 15 is turned until the N is in alignment with the NT on disc 13. When the dials are set as enumerated, it can be seen at a glance that North deals, the bid is 4 No-Trump not Vulnerable, was not Doubled or Redoubled.

East deals, a bid of 5 Hearts is made, Vulnerable and Doubled. The risc 13 is rotated until the Heart in one of the pyramidal pointers 32 is in line with the numeral 5 in one of the segmental areas 26 in the Vulnerable range on the disc 11. The pointer disc 15 is then rotated until the pyramidal pointer East is in line with Doubled under Hearts on the disc 13. When the dials are set as enumerated, it can be seen at a glance that East deals, the bid is 5 Hearts, Vulnerable and Doubled.

South deals, a bid of Little Slam in Spades made, Not-Vulnerable and Redoubled. Disc 13 is rotated until the Spade in one of the pyramidal pointers 32 is in line with L. S. in the area 29 Not-Vulnerable on disc 11. The small disc 15 is then rotated until the pyramidal pointer S is under Redoubled under Spades on disc 13. When the dials are set as enumerated it can be seen at a glance that South deals, the bid is Little Slam in Spades, Redoubled and Not-Vulnerable.

West deals, a bid of 3 Clubs, Vulnerable and not Doubled or Redoubled is made. Disc 13 is rotated until the Club in one of the pyramidal pointers 32 is in line with the numeral 3 in one of the segmental areas 26 in the Vulnerable range on the disc 11. The disc 15 is then rotated until the pyramidal pointer W is directly under Clubs on disc 13. When the dials are set as enumerated, it can be seen at a glance that West deals, the bid is 3 Clubs, Vulnerable, not Doubled or Redoubled.

From the foregoing description when taken in conjunction with the accompanying drawing, it can be seen that I have provided a device that is simple in operation, yet positive when properly set to indicate what has been bid, and I desire to have it understood that the showing is merely illustrative and that such changes may be made within the scope of the claims hereto appended. What is claimed is:

1. In a bridge-playing accessory, a base disc, a five-pointed disc rotatably mounted on said base disc, and a four-pointed disc rotatably mounted over said five-pointed disc, each of said discs having sectional markings, whereby the points on the five-pointed disc, representing the five suits, cooperate with the sectorial markings on said base disc to indicate the bid whether the bidder is vulnerable or not, and the points on the four-pointed disc, representing the four players, cooperate with the sectorial markings on said five-pointed disc to indicate the dealer whether the bidder was doubled, redoubled or not-doubled.

2. A bridge-playing aid, comprising a base disc, having an arcuate scale of points approximately 72° in length, a five-pointed disc pivoted thereon, said five points marked in sectors for the four units and for no trump, and cooperating with said arcuate scale to indicate the bid in accordance with the point which is set on the scale and its position thereon, to show whether the bidder is vulnerable or not, and a four-pointed disc rotatable on the same pivot over said five-pointed disc, said four points being marked N, E, S, and W for the four players, and cooperable with the sectors of said five points to indicate the dealer and whether the bidder was doubled, redoubled or not doubled.

3. The combination of a first disc having an arcuate scale extending approximately one fifth of a circumference, a second disc concentrically mounted for rotation therewith and being marked off into five sectors, each sector having indicia spaced annularly thereon and a point extending therefrom to cooperate with said arcuate scale, and a third disc similarly mounted over said second disc and having four points extending from its periphery for cooperation with said indicia.

4. The combination defined in claim 3, wherein said arcuate scale is marked off in points of bid for a bidder who is vulnerable and for one not vulnerable, and the five sectors are marked for the four different suits and for no trump, each sector's indicia being for "doubled," "redoubled" and "not doubled," whereby the position of one of the five points on the arcuate scale will show the bid, the vulnerability of the bidder, and the suit in which the bid was made.

5. The combination defined in claim 4, wherein the four points of said third disc are marked for the four players, whereby the location of one of these four points on the bidder's sector will show who the dealer was, and position of said point within said sector will show whether the bidder was doubled, redoubled or not doubled.

6. The combination defined in claim 5, wherein said four points are marked N, E, S, W.

7. The combination defined in claim 6, wherein said five points are marked by a spade, a heart, a diamond, a club, and N. T. respectively.

EDWARD W. PIPER.
